ASSIGNORS TO TOWLE MANUFACTURING COMPANY, OF NEWBURYPORT, MASSA-
CHUSETTS, A CORPORATION OF MASSACHUSETTS.

DISPLAY CHEST.

Application filed August 11, 1921. Serial No. 491,446.

To all whom it may concern:

Be it known that we, WILLIAM A. KINSMAN and HAROLD E. NOCK, citizens of the United States, residing at Newburyport, in the county of Essex, State of Massachusetts, have invented certain new and useful Improvements in Display Chests; and we do hereby declare the following to be a full, clear, and exact description of the invention, such as will enable others skilled in the art to which it appertains to make and use the same.

This invention relates to chests for containing silverware and the like, and more particularly to such chests as used for displaying flat silverware for inspection by purchasers.

In practical experience it has been found difficult to display flat silver or other similar ware in an artistic, pleasing manner so as to make the appeal desired for show purposes. As a consequence, flatware has seldom been displayed in windows or otherwise featured in display in the stores.

One object of the present invention, therefore, is to provide a chest which when closed may serve as a desirable container for the flatware, and when opened, the complete contents of the chest may be displayed effectively, partly in the body and partly in the cover of the chest, the construction being such that the relation of the parts for display purposes is predetermined by the formation and character thereof.

Heretofore it has been the custom to provide a container, in the form of a chest or other receptacle, with a bottom formation which presents separated supports for receiving each a plurality of pieces in nested relation, forming as a whole a rack for the pieces which is built into and forms a part of the container. To present a nice appearance and finish, the supports are covered with fabric, which also prevents the silverware from being marred. When so presented, pieces can be displayed only in a definite position as held by the unremovable rack. This is disadvantageous since the effect of a showing of the full depth or thickness of the nested pieces is lost, due to the height of the sides of the receptacle and the depth of the holding rack within it. Many other

disadvantages accrue from the use of a display chest of this character as will be apparent from the following description. 55

Another object of the present invention is to provide a display chest for silverware and the like which will obviate the disadvantage referred to and present new features which will permit a more advantageous display of the silverware, under varying conditions, than has heretofore been possible.

Accordingly, a feature of the present invention resides in the formation of a display rack having supports for receiving nested pieces of silver flatware which is unattached to the display chest. In other words, the rack, while receivable within the chest in the usual horizontal position for transportation purposes, is bodily removable therefrom and is portable for various purposes. The removability of the rack permits its arrangement within the chest for display purposes at such an angle that the form and design of the nested pieces can readily be scrutinized by intended purchasers; it permits the salesman to present to a purchaser the whole number of pieces in the rack for close inspection or handling to determine the weight of the silver, without disturbing the position of the chest itself in the show case or other display location; it permits the rack with its contained silver to be displayed independently of the chest 75 in locations where the chest is not suitable; it permits the racks with all of the pieces carried thereby to be removed from the chest as units, and the chest and the racks with their contents are individually so light 80 in weight that they may be moved separately, quickly and easily from place to place in the store; and, by selling the unattached rack as an article of merchandise, it permits the purchaser to transfer the silverware, while still held by the rack, and without handling, to the dining-room sideboard drawers. This latter use is particu-

larly advantageous since it permits the use of the rack as a holder of silver both in the drawer, while in use, and in the chest, while in storage, if the entire chest is sold as an article of merchandise. It will be understood that the number of portable racks, of 100

the character described, which may be employed with any particular chest will depend upon the size of the chest and the character of the display which is desired.

5 A further feature of the invention consists in the construction and arrangement of the chest to provide for an adequate display of the contained silverware under the varying conditions obtaining in different stores 10 where it is offered for sale. To this end, the cover of the chest is unhinged, so that it may be removed bodily, and means is provided in the form of adjustable cover supports for sustaining it in an open position at varying 15 angles to the top surface of the body of the chest, and with its lower edge below said surface if found desirable. With this arrangement, the chest may be used, without the cover, in a low show case, or any other 20 location, where the available height is insufficient to receive it with the cover raised. In such a case the silver racks may be set at an angle within the chest, or one laid obliquely on its upper surface or beside it. 25 Where the chest is used for display in a window, on a table, or other location where the cover may be used, the cover supports are adjusted for positioning the cover at the most advantageous angle for light and shade 30 and general attractiveness to the observer, and one of the portable racks is then laid against it. In order to sustain a rack or other display piece on the cover, when in its angular position a feature of the invention 35 comprises means in the form of a belt molding on the under side of the cover constructed to hold said piece in position thereon. An important characteristic of the molding is that its arrangement and location 40 is such that it not only serves adequately to present to purchasers a display piece, such as one of the portable racks, but also serves to locate the removable cover on the body of the chest when the chest is 45 closed.

These and other features of the invention, including certain details of construction and combinations of parts will be further explained in the following description and 50 then pointed out in the appended claims.

The preferred form of the invention is illustrated in the accompanying drawings, in which:—

55 Figure 1 is an elevation with the cover on; Fig. 2 is a plan with the cover off; Fig. 3 is an under side plan of the cover; Fig. 4 is a section on the line 5—5 of Fig. 2 with the cover on and racks in storage position; Fig. 5 is a side view of one of the cover 60 supports; Fig. 6 is a transverse section of the chest open with the racks in display position; and Fig. 7 is a perspective view similar to Fig. 6.

65 In the embodiment of the invention illustrated in the drawings the chest is shown as

of rectangular form with an exterior configuration providing parallel fillets and mouldings combined in a manner to present a pleasing appearance. The preferable material used is mahogany but a particular material is not essential, as will be understood from the following description, nor is any special shape or exterior configuration essential, except that a chest polygonal in plan lends itself to the most effective use of 70 the features of the invention.

The chest comprises a hollow body portion 10 and an unhinged cover 11 which closes an opening at the top surface of the body. The inner edge of the surface formed by the 80 upper ledge of the side walls is provided with a marginal rabbet forming a peripheral exterior shoulder 12. The underside of the cover is formed with a belt molding 13 providing a marginal shoulder of such proportions as to be seated within the body shoulder 12 when the cover is in closed position. The area of the opening presented by the molding 13 is the same as the area of the opening in the body as shown by Fig. 4. 90

Within the chest are front and rear, longitudinal cleats 14 and 15 about midway the height of the walls thereof; and in the floor of the chest, below the rear cleat 15 are two rectangular openings 16. Adapted to be seated in said openings 16 are two cover supports 17 (Fig. 5) of some material capable of being flexed to vary its shape and to retain its new shape. These cover supports are preferably in the form of flexible inelastic strips, covered with a textile material to prevent marring the chest. Each provides a lower portion 18 which enters an opening 16, an upper portion 19 which extends obliquely thereto, and an intermediate portion 100 shaped to form a shoulder 20 which may be employed as a seat for one edge of the removable cover.

In Fig. 4 two racks, for the silver to be displayed, are shown in the position they 110 occupy when the cover is closed. One rack 21 rests on the floor of the chest and the other rack 22 rests on the cleats 14 and 15. Their size is such as to fill the space presented by the opening in the chest. These 115 racks are not secured to the chest in any form or manner but are separate, portable units that may be freely removed and handled individually outside the chest. The racks comprise a relatively thin base-board 120 having thereon supporting means for removably receiving in spaced relation a plurality of nested piles of different pieces of flatware, and a soft covering material, such as velvet, over said means. The chest, also, is lined throughout its interior to match the removable racks. 125

Having thus described the constructional features of the chest, the manner of its use for display of the contained silver will now 130

be set forth. Where the display is to be made in a window, on a table, or other location where there is ample head room, the cover supports 17 are given a shape and 5 form substantially as shown in Fig. 5 and, after removing the unhinged cover 11, the ends 18 of the supports are seated in the openings 16 as shown in Fig. 6. One edge of the cover may now be seated on the shoulders 20 which depend at the back of the chest and the top of the cover rests against and is supported by the oblique portions 19. One of the removable racks is then taken 10 from the chest and laid on the cover, within the peripheral molding 13 which, as heretofore described, presents an opening of the 15 dimensions of the rack and, therefore, acts to hold and sustain the rack in display position on the cover. The obliquity of the portions 19 of the cover supports to the surface of the chest is determined by the position of the chest relative to the observer and is so selected as to produce the best possible effect 20 of the displayed silver. The second rack is then lifted into the oblique position shown 25 in Fig. 6 with its rear surface resting against the supports 17 and its front edge resting on a block 23, which is placed within the chest against its front wall for this purpose.

30 The display need not be limited to a use of the two contained silver racks but, if space permits, two additional racks of the same character may be placed beside the chest. This permits a unit display presenting a complete set of silverware. Furthermore the use of the cover as a support is not limited to sustaining a rack. Many stores that carry flatware cannot afford to carry hollow ware. In order to permit such stores 35 to give to the observer a knowledge of the character and design of the hollow ware, which matches the displayed flatware, the cover may be used as a holder to sustain a display piece such as a framed photograph or other illustration, of a tea set or other pieces of hollow ware in the dinner service of the same design as the flatware displayed in the remaining rack or racks.

40 In many stores the display must necessarily be made in a position where there is restricted head room, such as in a counter or a wall show case. The advantage of the unhinged, removable cover in such locations is readily apparent. It is not possible to arrange an open chest having a hinged cover in such cases, but with the present chest the cover supports can be bent to such form as to drop the cover seats down below the upper edge of the rear wall to the amount required to permit the cover still to rest thereon in the restricted head room and at the proper angle to adequately display the silver sustained thereby.

45 A chest of the present character embodying freely removable racks for holding the

silver is of immense advantage to the house-keeper. The racks may be placed intact in the sideboard drawers and used regularly as holders for dining room flatware, thus 50 keeping the flatware in proper sorted order; and the racks may be taken from the sideboard drawers or from the chest itself, and used as trays from which the pieces are removed as wanted in setting the table. This 55 leaves the unused pieces in an orderly arrangement and saves time and trouble in making the required selection and arrangement on the table.

It is particularly pointed out that the construction and arrangement described permits a mass display of the silverware, and those skilled in the art are well aware of the merchandizing value of such a display. In one 60 rack flatware may be displayed in piles, and in another the knives are grouped close together, while both racks are in close proximity to each other, all of which is permitted by the provision of removable silver racks.

65 The construction and shape of the chest give it an ornamental appearance which desirably combines with the structural features in effectively displaying the ware.

70 The nature and scope of the present invention having been indicated and the preferred form of the invention having been 75 specifically described, what is claimed as new is:—

75 1. A display chest for pieces of silverware and the like having a body, a removable cover, and a plurality of cover supports removably sustained by the body projecting upwardly and outwardly therefrom, said supports being shaped to form a seat 80 for receiving an edge of the cover and holding it at the rear of the body and at an angle to the surface thereof.

85 2. A display chest for pieces of silverware and the like having a body, a removable cover, and a plurality of strips of flexible inelastic material held within the body 90 at one end and projecting upwardly and inclined outwardly from said body, with intermediate cover seats, whereby the cover may, when removed, be supported edgewise by said strips in varying positions relative 95 to the surface of the top of the body by varying the angular relation of the outwardly inclined portions and seats of said strips to the portion within the body.

100 3. A display chest for pieces of silverware and the like having a body, having recesses in the floor thereof to receive the lower ends of a plurality of flexible inelastic strips, said strips, having a form to present shoulders at the rear of one wall of the body and thence extending upwardly and obliquely relatively to said wall, and a removable cover adapted to be supported by said strips with one edge resting on said shoulders.

4. A display chest for pieces of silverware and the like comprising a body and a cover, racks for the pieces mounted in the body and removable therefrom, said body having provision for supporting one of the racks therein in inclined display position, and said cover having provision for supporting and displaying a rack wholly removed from the body, and means to support the cover in open position.

5. A portable holder or tray for pieces of silverware in the form of a lightly constructed, lidless rack adapted to be set loosely, like a tray, in a storage chest, sideboard drawer, or similar repository, said holder comprising supporting means secured thereto for removably receiving in spaced relation a plurality of piles of different pieces of flatware, each pile comprising like pieces superimposed on each other in nested relation, and soft covering material over said means to prevent marring the pieces and also over the holder.

6. A portable holder or tray for the flat-

ware of a dinner service comprising a flat 25 and relatively thin, lidless base-board having on one surface supporting means providing a plurality of open slots normal to the plane of the base-board and each of such depth as to permit the introduction 30 therein of a number of pieces in nested relation, the construction also providing for a compact arrangement on the base-board of the required variety of pieces for a course dinner, and soft covering material 35 about and in said slots and also over the base-board, whereby a complete combination of pieces as described may be lifted, carried and transferred without effort to and from a storage chest, sideboard drawer 40 or similar repository and the dinner table, said holder loosely reposing in the repository in the form of a readily removable and portable open, tray-like rack from which the silverware may instantaneously 45 be removed.

WILLIAM A. KINSMAN.
